LATE NEWS PLATE CASTING MACHINE

Original Filed Jan. 19, 1927 2 Sheets-Sheet 2

UNITED STATES PATENT OFFICE

HENRY A. WISE WOOD, OF NEW YORK, N. Y., ASSIGNOR TO WOOD NEWSPAPER MACHINERY CORPORATION, OF NEW YORK, N. Y., A CORPORATION OF VIRGINIA

LATE NEWS PLATE CASTING MACHINE

Application filed January 19, 1927, Serial No. 162,116. Renewed March 16, 1931.

This invention relates to the casting of late news plates which are to be inserted in the ordinary stereotype plates for printing articles of news which come in too late to be incorporated on the regular printing plates.

The principal objects of the invention are to provide a method of casting these late news plates which will avoid the necessity of having a linotype operator make up as many 10 duplicate slugs of the late news device as there are duplicate printing plates used in the edition; to provide means whereby these late news plates can be cast in a manner similar to the usual stereotype printing plates but 15 with a small casting machine capable of producing more than one plate at an operation, when desired; to produce means whereby the said casting machine is operated automatically for this purpose; to provide means for 20 holding a plurality of matrices in the concave back of said casting machine; to provide means for operating two complete sets of matrix clips therein, and to provide means for ejecting the plates automatically one 25 after the other with the rotation of the core or cylinder and sawing off the tails.

Other objects and advantages of the invention will appear hereinafter.

Reference is to be had to the accompanying drawings in which

Fig. 1 is a plan of a late news plate casting device constructed in accordance with this invention showing the parts in position for performing the casting operation;

Fig. 2 is a similar view showing the trimming and delivery of the plates;

Fig. 3 is a central vertical sectional view on the line 3—3 of Fig. 1.

Fig. 4 is an elevation of one of the matrix 40 clips; and

Fig. 5 is an enlarged plan thereof.

Ordinarily a late news printing device consists of a collection of linotype slugs held in a suitable holder. Late news is generally 45 printed on a portion of the newspaper which is left blank for that purpose and reserved for news that comes in too late to be cast into the regular printing plate. The late news device therefore has to be made up with the greatest possible economy of time and effort at the last

moment before going to press. Each one is set up by a linotype operator and these linotype slugs constitute the printing surface of the printing member of the couple. Each one is fastened to a cylinder especially reserved 55 for it.

Under present conditions the larger newspapers are printed in such great editions that it is necessary to have duplicate plates and cylinders for the same edition of the paper. 60 In such cases it is necessary for the linotype operator to make up just as many sets of slugs for the late news as there are duplicate plates for use in printing the papers. This causes a waste of time just when time is most valuable, that is, the last period before going to press.

The purpose of this invention is to make up a single linotype slug as a master, the same as in the preparation of a regular stereotype 70 plate. From this a matrix is made as in the general process of stereotyping. As many of these matrices may be made as are necessary. They are used to cast late news plates of less than page size which are to be used in connection with the usual plates with blank spaces 75 that are made up for their insertion as the news comes in. This reduces the time required by the linotype operators and is of very great value for the reason that the press 80 has to wait only for a single set-up by the linotype operator and then for the casting of as many of these partial late news plates as may be desired.

On account of the customary size of the late news section I find it possible to cast two late news plates against the periphery of the cylinder or core. This cylinder is of the usual stereotype plate diameter but of about half the customary length of a stereotype core for 85 making the ordinary plate. These late news plates are of less than a semi-circle in width, of course. In fact, if two are cast they are both cast on a semi-cylindrical surface of the core. Therefore the matrix is stripped by 90 merely pulling the back away and no such complication is involved here as in an ordinary stereotype mold because they do not pass half way around the cylinder.

I have shown a machine for carrying out 100

this invention which comprises a frame or bracket 10 fastened to the side of a melting furnace 11. The furnace, of course, is provided with the usual melting pot and may be 5 provided with any desired means for filling the mold. This bracket 10 is pressed against the furnace by a foot 12 and supports the entire machine.

The power is supplied from any desired 10 source to a driving gear 13 mounted on a shaft 14 supported in bearings on this bracket 10. This shaft has a worm 15 thereon driving a gear 16 located on a vertical shaft 17 supported by the bracket 10. On the shaft 17 is 15 a cam 18 having a cam groove 19 for receiving a roll 20 which is adjustably fastened to a shelf 21 which projects out rearwardly from the casting back 22 forming a part of the mold. This back and shelf are mounted to 20 slide in a rectilinear direction, being guided in ways or guides 23 on the bracket 10. The cam groove 19 is so designed that for a major portion of the cycle, that is for one rotation of the shaft 17, the casting back 22 is forward 25 in casting position permitting the plate to be poured and cooled. It is also equipped with a low portion which withdraws the back 22 and holds it in that position. During this portion of the cycle a gear 25 on the bottom 30 of a journal 26 which supports and carries with it the casting core 27 is rotated by a segmental set of gear teeth 28 fixed to the gear 16. This segment 28 has just enough teeth on a portion of its periphery to cause the cylinder 27 to rotate through a half revolution and come to a stop when the groove 19 is just 35 ready to cause the back 22 to advance into position for casting more plates. On the shelf 21 are two vertical shafts 29 on which 40 are fixed casting bar levers 30 at opposite sides. On these shafts are arms provided with cam rolls 31 operating in cams 32 fixed to the guides 23. The motion of the box 22 toward and from the casting position swings 45 the levers to cause the casting bars 33 to open and close, as will appear from a comparison of Figs. 1 and 2. This is for the obvious purposes of opening and closing the opposite edges of the mold formed between the back 50 22 and the cylinder 27.

The matrices are clamped in the box by means of a removable vertical bar 35 in the center which engages the adjacent edges of two matrices and clamps them in place against 55 vertical rods 40. The bar 35 is moved up and down by a hand lever 34.

Two matrix clips 36 clamp the matrices on their outer edges. These clips are moved toward and from clamping position by means 60 of handles 37 pivoted on studs 38 at the extreme edges of the casting box. The handles carry pins 39 entering horizontal slots in the clips. These pins cause the clips to move up or down as the handles are operated. The studs 38 acting in inclined slots 41 cause the

clips to move into clamping position as shown in Fig. 1 or to recede from the matrix when the handles are pulled up.

It will be seen that I have shown two matrices M clamped in position in this way. 70 These matrices cover an arc of less than 90 degrees and in fact considerably less. On account of their small curvature no means has to be provided for stripping the matrix from the plate when the casting box is open. It 75 will be understood, however, that they are of the same kind as the matrices used in casting full plates, but the whole mold is much shorter.

The cylinder 27 is provided with one or 80 more circumferential grooves 44 in which fit rings 45 which are stationary. These rings are provided with strippers 46 that project toward the core or cylinder 27 and strip the plates and tails. The strippers are carried by the fixed guides 23 and in turn support the rings 25. I have shown two of these rings and strippers, one for the plate and the other for the tail. They pry the castings away from the cylinder if there is any tendency for 90 them to stick to it. On the cylinder 27 are recesses 27^a into which project tongues or 95 ridges from the tails of the casting plates to hold the tails in place on the cylinder after they are sawed off.

The cylinder is cooled by means of a pipe 48 delivering water to two or more pipes 49 which are open at the bottom. They admit water into a trough formed by the side of the cylinder 27 and a cylindrical partition or 100 jacket 50 centered inside the cylinder. When this space is filled, the water flows over the top of the jacket and escapes through a passage 51 in the bottom into a chamber 52 and then through an outlet pipe 53.

For the purpose of cutting the tails from the plates I provide a tail cutting saw 55 on a vertical shaft 56 rotated by bevel gearing 57 on the shaft 14. This saw rotates constantly and in contact with the cylinder so that as the 110 plates are delivered by the rotation of the cylinder the saw will cut all the risers from their respective plates. Then both tails and plates are separated from the cylinder by the strippers 46.

This machine will cast as many duplicate late news plates of standard thickness as may be desired from matrices molded in the ordinary way from a single set-up of linotype matter. Only one or two matrices need be 115 molded for any run. By the use of these matrices this machine rapidly produces a large number of plates therefrom effecting obviously a great saving of time. The use of two plates of less than 90 degrees arc in the width 120 on one half of the cylinder does not require the stripping of the matrices from the plates when the box is open. This is because the plates do not go half way around the cylinder and consequently do not cling to it. 130

The strippers are used to be sure to separate the plates and tails if they adhere to the surface of the cylinder.

It will be seen therefore that these late news plates can be cast with sufficient speed so that the late news matter can be provided as fast as it can possibly be needed in the last period before going to press. Furthermore all the plates will be alike and not dependent upon a new set-up of the linotype matter at any time. The linotype operator usually can take a little more time than heretofore, thus increasing his accuracy.

Although I have illustrated and described only a single form of the invention I am aware of the fact that modifications can be made therein by any person skilled in the art without departing from the scope of the invention as expressed in the claims. Therefore, I do not wish to be limited to all the details of construction herein shown and described, but what I do claim is:—

1. In a mold for casting a late-news insert plate, the combination with the concave back and cylindrical core, of a matrix in the back extending only part way around its concave surface, and means for completing the mold at the edges of the matrix.

2. In a stereotype plate casting machine, the combination with a rotatable core and a back having a width of less than a semi-circle and adapted to co-operate with the core, of a vertical shaft, a cam on the shaft connected with the back for moving the back toward and from the core, said cam having a shape to hold the back in casting position during the major portion of a single rotation of the shaft and to hold it back in open position during a small part of the revolution, a segmental gear rotated by said shaft having a few teeth located opposite the low part of the cam, and a gear on the core adapted to mesh with the teeth on the segment gear when they come around to rotate the core less than a complete revolution to deliver the castings.

3. In a stereotype plate casting machine, the combination with a rotatable core and a back adapted to co-operate with the core, of a shaft, a cam on the shaft connected with the back for moving the back toward and from the core, a segmental gear rotated by said shaft having a few teeth located opposite the low part of the cam, and a gear on the core adapted to mesh with the teeth on the segment gear when they come around to rotate the core to deliver the castings.

4. In a stereotype plate casting machine, the combination with a cylindrical core, of a segmental back having an effective casting width materially less than a semi-circle, an operating shaft, a cam on the shaft connected with the back for moving it toward and from the core, a support for the casting machine having a pair of guides thereon, and a shelf projecting backwardly from the back

movable in and guided by said guides to cause the back to move in a rectilinear manner.

5. In a casting machine, the combination with a melting furnace, of a bracket supported thereby and a casting box supported on the bracket and comprising a rotatable cylindrical core, a segmental back, and means on the bracket for guiding the back to move in a rectilinear radial direction away from the core for opening the mold and toward the core for closing it.

6. In a stereotype plate casting device, the combination with a core and a back for casting late news plates, of means for holding a matrix therein, stationary ways, a guide on the back movable in said ways, means for moving the back toward and from the core in the ways, cams on the ways, a pair of casting bars, and means whereby the reciprocation of the back will move the casting bars into and out of casting position.

7. In a stereotype plate casting device, the combination with a cylindrical core and a back having a casting space of less than a semi-circle for casting late news plates, of means for holding a matrix therein of the same size as the plates, stationary ways, a guide on the back movable in said ways, means for moving the back toward and from the core in the ways, cams on the ways, a pair of shafts having arms projecting therefrom one pair being guided in said ways, whereby when the back is drawn back the shaft will be turned, and casting bars carried by the arms on the shaft.

8. In a stereotype plate casting device for casting late-news plates, the combination with a core and back, of a straight longitudinal matrix bar at the center slidable longitudinally and having means for engaging the inner edges of two matrices in the back, and a pair of matrix clips for engaging the outer edges of said matrices and movable for clamping them in position.

9. In a stereotype plate casting box for late-news plates, the combination with a core and back, of a bar on the back slidable longitudinally for engaging and clamping the inner edge of a matrix in the mold, a matrix clamp for the outer edge having slanting slots therein, pins projecting into said slots, and means for moving said pins to force the clips inwardly to hold the matrix at that edge.

10. The combination with a mold for casting a plate and a matrix in the mold against which the plate is cast, of a stationary circular ring set into the core, said ring having a surface projecting from the circumference of the core for ejecting the cast plates when the core rotates.

11. In a stereotype plate mold having means for supporting a plurality of matrices and producing simultaneously a plurality of late news plates, the combination with a rotatable

core and a concave back, of a pair of rings set into recesses in the core and held in stationary position as the core rotates, said rings having projections constituting strippers for engaging the plates as they come around and detaching them from the core, one of said rings and strippers being located in position to strip the tails from the core.

12. In a stereotype plate mold having means for producing plates, the combination with a rotatable core and a concave back, of a ring set into a recess in the core and held in stationary position as the core rotates, said ring having a projection constituting a stripper to strip the tails from the core.

13. In a machine for casting stereotype late news insert plates against matrices, the combination with a rotatable core, a back, said back having means for holding a plurality of matrices, and means for rotating the core a half revolution at a time to take all the castings out of the back and present them in position for delivery, of a saw rotatable on an axis parallel to that of the core constantly during the operation of the machine and in contact with the core for severing the tails from the castings one after another.

14. In a casting device for the purpose described, the combination with a central core, of a back having a plurality of mold cavities for simultaneously casting a plurality of plates circumferentially around said core.

In testimony whereof I have hereunto affixed my signature.
